CLAIM

The ornamental design for an electrical connector assembly, as shown and described.

DESCRIPTION

FIG. 1 is a perspective view of an electrical connector assembly in a decoupled state, showing my new design; FIG. 2 is a side view thereof in a coupled state, the opposite side view being substantially identical;

FIG. 3 is an end view thereof;

FIG. 4 is another end view thereof;

FIG. 5 is another side view thereof; and,

FIG. 6 is yet another side view thereof.

The broken lines showing the conductors in FIGS. 1, 2, 3, 4 and 6 are included for the purpose of illustrating environmental structure only and form no part of the claimed design.
